United States Patent Office

Des. 177,761
Patented May 22, 1956

177,761

COMBINED CAN AND CLOSURE CAP THEREFOR

Herman E. Reinhardt, Hasbrouck Heights, N. J., assignor to Boyle-Midway Inc., New York, N. Y., a corporation of Delaware

Application August 13, 1954, Serial No. 31,866

Term of patent 14 years

(Cl. D58—17)

Fig. 1 is a bottom perspective view of a combined can and closure cap therefor showing my new design;

Fig. 2 is an elevational view thereof, with parts shown broken away for convenience of illustration; and

Fig. 3 is a bottom plan view thereof.

I claim:

The ornamental design for a combined can and closure cap therefor, as shown and described.
